[57] CLAIM

The ornamental design for a holder for kitchen utensils and the like, as shown and described.

DESCRIPTION

FIG. 1 is a perspective view of a holder for kitchen utensils and the like showing our new design;

FIG. 2 is a right side elevational view thereof, the opposite side being identical;

FIG. 3 is a top plan view thereof;

FIG. 4 is a front elevational view thereof; and,

FIG. 5 is a rear elevational view thereof.

The undisclosed bottom view is unornamented.
